HORN

Application filed July 5, 1928. Serial No. 290,557.

This invention relates to horns and particularly to the class in which sound waves are increased or magnified, the principal object being to provide such a horn which is 5 light in weight, compact, strong in construction, and exceptionally economical to manufacture.

Another object is to provide a horn of the sound amplifying type with a natural highly 10 polished inner surface whereby friction is at a minimum so that the sound waves will travel unhindered and will be reproduced with increased volume without distortion.

Another object is to provide a horn of the sound amplifying type in which sound waves will be produced in their original rendering with increased volume and will not be affected by dampness and normal temperature 15 changes.

20 A further object is to provide a horn of the sound amplifying type which is formed from celluloid, pyralin or similar materials.

A still further object is to provide a horn 25 of the sound amplifying type formed of two celluloid members having convolute grooves therein, the members being secured together with the grooves in matched relationship to provide an amplifying passageway.

These being among the objects of the present 30 invention, the same consist of certain features of construction and combinations of parts to be hereinafter described with reference to the accompanying drawing, and then claimed, having the above and other objects in view.

This invention is particularly adaptable to that type of horn commonly known as a loud speaker to increase or amplify the sounds transmitted by a radio or wireless apparatus, 40 although the loud speaker is equally as adaptable to produce the sounds produced by a talking machine or other instruments of this character.

The horn is constructed of sheet celluloid 45 or pyralin which is formed to the desired shape by a process which is the subject matter of another application. Celluloid has many characteristics which renders the same very suitable for a sound amplifying horn, one of which is that the surface of the same

is highly polished and it is therefore, very desirable to use because friction is reduced to a minimum and the sound waves pass through the amplifier unhindered. This feature allows the sound waves to be produced 55 with increased volume and mellowness without distortion. Celluloid is a non-metallic material and a horn built of this material will not emit the harsh metallic sounds which are so prevalent in some of the other types of 60 loud speakers used in the past. Another feature which is highly desirable is that celluloid is not porous and will not be affected by dampness or changes in temperature. Many 65 of the horns previously built were of plaster of Paris or other porous material which absorbs moisture on damp days which does not allow musical notes to be produced with mellowness and fine quality of tone. Celluloid can be produced in a variety of colors which 70 may match with furniture and the like. Another striking advantage of celluloid is that it is very light in weight but is very strong and rigid, therefore making the same very desirable to use as it can be carried from place 75 to place without any great effort. A further advantage is that by reason of its lightness and narrowness, the horn of my invention is readily adaptable for use in automobiles 80 equipped with radio receiving sets.

In the accompanying drawing which illustrates a suitable embodiment of the present invention,

Figure 1 is a side elevation of the completely assembled horn mounted upon a suitable reproducing unit.

Figure 2 is a transverse section through the horn taken on the line 2-2 of Figure 1.

Figure 3 is an elevation of one of the horn members looking toward the convolute groove 90 therein showing the outlet opening.

Figure 4 is an elevation of the other horn member looking toward the convolute groove therein.

Figure 5 is an enlarged section taken on 95 the line 5-5 of Figure 4 showing the gradual decrease in thickness of the horn material at points farthest away from the parting plane.

Referring to the accompanying drawing in which like numerals refer to like parts 100

throughout the several views, the loud speaker or sound amplifier is built up of two sections 10 and 11, each being formed to shape from a single piece of sheet celluloid or similar material.

The section 10 is formed to the shape shown in Figure 3 and is provided with a semi-circular groove 12 therein arranged in a spiral form, the same preferably having at least two complete turns. The groove 12 coils inwardly in a counter-clockwise direction and gradually increases in width as the same approaches the center of the section 10. The entrance to the groove 12 is at the end having the smallest width and is enlarged at 13 for a purpose to be described later. Similarly the section 11 is formed to the shape shown in Figure 4 and is provided with a semi-circular convolute groove 14 therein of the same size as the groove 12 which coils inwardly in a clockwise direction and gradually increases in width as the same approaches the center of the section 11. The entrance to the groove 14 is enlarged at 15 for a purpose to be described later.

The two sections 10 and 11 are secured together by cementing the webs 16 between the turns of the groove 12 to the webs 17 between the spiral turns of the groove 14. Celluloid is capable of being dissolved and for this reason two celluloid parts can be very efficiently and satisfactorily secured together by dissolving the surfaces and forcing them into contact with each other. In the present invention, the webs 16 and 17 of the two sections 10 and 11 are coated with acetone or similar substance which causes the surfaces thereof to fuse or dissolve. These surfaces are then brought into contact with each other under pressure. When these surfaces are fused together, a solid unbreakable joint is provided which can be compared to a welded joint between two pieces of metal.

When the two sections 10 and 11 are secured together in this manner the grooves 12 and 14 are in matched relationship and a section thru the same presents a circular passageway 18 arranged in spiral form as shown in Figure 2. The passageway 18 is of small diameter at its outer end which is the sound inlet and gradually increases in diameter up to the outlet 19 which is provided for by cutting away a portion of the celluloid comprising the end of the groove 12 in the section 10. The enlarged entrances 13 and 15 of the grooves 12 and 14 respectively when combined provide a cylindrical opening which receives the discharge end of a reproducing unit 20. The reproducing unit 20 is mounted upon a base block 21 which also provides support for the sections 10 and 11.

It will be noted in Figure 5 that the celluloid surrounding the opening gradually decreases in thickness as a chord perpendicular to the plane of separation of the passageway

18 increases in length. This feature increases the quality of the tones produced, since the walls are of greater thickness adjacent the common plane of the convolute curve than at points farthest away from this plane.

It is apparent from the foregoing description that a sound amplifier constructed from cellulose material to the shape shown has many advantages over amplifiers used in the past.

The features which make the amplifier of the present invention more advantageous than other types are as follows:

Light in weight, making the same portable and light enough to hang upon a wall without danger of falling.

Extremely economical to manufacture as the same is constructed of only two celluloid sheets molded to the proper shape.

Natural extremely smooth passageway surface which reduces friction to a minimum thereby reproducing tones in their original rendering.

Gradual decrease in thickness of the passageway walls as the chord perpendicular to the convolute plane increases in length, which improves tone qualities.

Extremely compact thereby requiring small mounting space but with an exceedingly long passageway for its size.

Adapted to be produced in colors to match furniture and the like.

Not affected by dampness and normal temperature qualities thereby giving perfect amplification at all times.

It is to be understood that formal changes may be made in the specific embodiment of the invention described without departing from the spirit and substance of the broad invention, the scope of which is commensurate with the appended claims.

What I claim is:—

1. A sound amplifying device constructed of celluloid-like material, having a sound amplifying passageway therein of convolute form gradually increased in area from the inlet to the outlet thereof, the walls of said passageway being decreased in thickness as the chord perpendicular to the convolute plane is increased in length.

2. A sound amplifying device comprising two members of celluloid-like material secured together, each of said members being formed from a single sheet of celluloid-like material, and a continuous sound amplifying passageway between said members, one of said members having an outlet opening for said passageway.

3. A sound amplifying device comprising two members of celluloid-like material secured together having semi-circular grooves therein arranged in convolute form in matching oppositely-disposed relationship to each other to provide a circular sound amplifying passageway, an inlet for said passageway,

and an outlet for said passageway in one of said members adjacent the central axis of said device, said passageway being gradually increased in area from said inlet to said outlet.

5 4. A sound amplifying device comprising two members of celluloid-like material secured together having semi-circular grooves therein arranged in convolute form in matching oppositely-disposed relationship to each 10 other to provide a circular sound amplifying passageway of increasing area from the inlet to the outlet thereof, and sound reproducing mechanism for said inlet, said outlet for said passageway being formed in one of said 15 members.

5. A sound amplifying device comprising two members of celluloid-like material, each having a continuous convolute groove semi-circular in section and of gradually decreasing 20 radius, said members being secured together with their grooves presented toward each other, thereby forming a convolute smooth-walled passageway of gradually increasing diameter from the inlet to the outlet 25 for the transmission and amplification of sound waves.

Signed by me at South Bend this 30th day of June, 1928.
